UNITED STATES PATENT OFFICE.

HELMER JOHN BOE, OF CHICAGO, ILLINOIS, ASSIGNOR TO WESTERN ELECTRIC COMPANY, INCORPORATED, OF NEW YORK, N. Y., A CORPORATION OF NEW YORK.

HOUSING.

Application filed June 21, 1924. Serial No. 721,608.

This invention relates to housings, and more particularly to housings comprising a plurality of cooperating members or sections.

- 5 An object of the invention is to provide a housing comprising a plurality of sections which can be quickly and easily brought into and out of their functionally operative positions.
- 10 A further object of the invention is to provide a housing comprising a plurality of cooperating sections of which one section is adapted to hold the other in an adjusted position.

15 A still further object of the invention is to provide a housing comprising a plurality of sections wherein a displacement of one section will be accompanied by a displacement to a different degree of the other section.

20 A housing embodying one form of the invention is employed as a guard upon a machine adapted to insulate wires which are to be used as electrical conductors. The guard is associated with the serving mechanism 25 of the machine and comprises a plurality of complementary sections pivotally mounted upon axes disposed at an angle to each other. This construction enables the operator to bring the sections into and out of positions wherein they enclose the serving mechanism, it being necessary to open the housing when the supply of insulating material is to be replenished. Means is provided for operatively connecting the sections 30 so that displacement of one of the sections is accompanied by displacement to a larger degree of the other. Thus, the operator need only displace one of the sections when the housing is to be opened or closed. The 35 section opened to the larger degree is adapted to hold the other section in its open position.

Other objects of the invention will become apparent as the detailed description progresses, reference being had to the accompanying drawing, wherein

Fig. 1 is a front elevation of a paper insulating machine wherein a guard embodying the invention is provided;

50 Fig. 2 is an enlarged fragmentary front elevation of a paper insulating machine, several means or parts of the guard being shown in changed positions;

Fig. 3 is a plan view of a guard embodying the invention, and

Fig. 4 is a fragmentary section taken on line 4—4 of Fig. 2.

Referring to the drawing, the reference character 10 designates in its entirety a housing embodying the invention, the housing being employed as a guard upon a paper insulating machine of a well-known type. The paper insulating machine comprises a frame 11 wherein a supply reel 12 and a take-up reel 13 are rotatably journaled. Suitable means (not shown) are provided for driving the take-up reel 13 so that it will draw the wire to be insulated from the supply reel 12, the wire being drawn through a serving mechanism indicated at 14 and over a capstan 15. In this instance, the serving mechanism 14 is adapted to apply paper in ribbon form to the wire as it is advanced through the serving mechanism, the serving mechanism being rotated at high speed during the operation of the machine. The serving mechanism comprises a disk 16 which supports a narrow roll of the paper to be applied to the wire. It is of course necessary that the supply of paper upon the disk 16 be replenished from time to time and for this purpose a plurality of narrow rolls of paper indicated at 17 rest upon a bracket 18 from which position they may be lowered one at a time to the disk 16. However, because of the high speed at which the serving mechanism rotates, it is advantageous to have it covered during the operation of the machine so that the operator cannot come in contact with the rapidly rotating mechanism. At the same time, it is desirable that the housing be so constructed that the operator can quickly and easily bring it out of its protecting position to permit a renewal of the supply of paper upon the disk 16.

The aforementioned housing or guard 10 affords ample protection to the operator and does not impede the efforts of the operator when the supply of paper upon the disk 16 is being replenished. The housing or guard 10 comprises a plurality of sections 20 and 21 rigidly secured to a plurality of shafts 22 and 23, respectively. The shafts 22 and 23 are disposed at right angles to each other and are rotatably journaled in a plurality of

bearings 24 mounted upon the frame 11 of the insulating machine. Rigidly secured to the shaft 22 is a bevel gear 25 which meshes with a bevel gear 26 secured to the shaft 5 23, the gears being so proportioned that angular displacement of the section 20 is accompanied by a larger angular displacement of the section 21. The section 20 is provided with a handle 27 whereby the operator may 10 bring the section into the position wherein it is shown in Fig. 2, when the supply of paper upon the disk 16 is to be renewed. This displacement of the section 20 is accompanied by a larger displacement of the section 21 which 15 is brought into the position wherein it is shown in Fig. 4. The section 21 is provided with a lug 28 which functions as a stop and limits the displacement of the sections 20 and 21 with respect to their closed positions, as 20 shown in Fig. 4, the lug 28 is adapted to engage the frame 11 when the section 21 has been brought into a position wherein it tends to rotate in a clockwise direction and to hold the section 20 in its open position. The arrangement is such that the section 20 need only be brought to an upright position when the guard is opened in which position it does not interfere with the wire trained between the capstan 15 and the take-up reel 13. This 25 arrangement is advantageous in that the machine can be built compactly, thus facilitating the task of the operator who generally handles five machines placed side by side and operated from a common drive shaft.

30 35 It will be noted that each of the sections 20 and 21 comprises an arcuate flange 29 and the substantially flat top wall 30. It will also be noted that each of the flat walls 30 is provided with an arcuate notch 31, the 40 notches 31 being so disposed that they form an opening through which the wire being insulated may be drawn. It is apparent that the sections 20 and 21 can be brought into and out of their functionally operative positions without injury to the wire which is be-

ing advanced through the serving mechanism or to any insulation which may have been applied to the wire.

What is claimed is:

1. A housing comprising a plurality of hinged sections pivoted at right angles to each other, means for positioning the sections to form a composite enclosure for mechanism, and means including co-operating bevel gears for separating and withdrawing all of the sections from their enclosing positions to permit access to the mechanism when one of said sections is withdrawn.
2. A housing for mechanism comprising a hinged section having a cut-out sector to surround a projecting portion of the mechanism, a second section hinged at right angles thereto and having a similar sector, means for aligning the sectors to form an aperture in the housing when closed, and means including co-operating bevel gears for moving one of the sections when the other section is moved.
3. A housing comprising a pair of substantially semi-circular sections having depending portions adapted to shield an operating mechanism, means for mounting said sections on axes at right angles to each other, and means interconnecting said means responsive to the movement of one section to cause the movement of the other section through a greater angle.

4. A housing comprising a pair of sections, each of said sections having an arcuate flange and a substantially flat top wall members on which said sections move, and means including gears interconnecting said members responsive to the movement of one section for causing the movement of the other section.

In witness whereof, I hereunto subscribe my name this fourth day of June, A. D., 1924.

HELMER JOHN BOE.
